(57) **CLAIM**

The ornamental design for a crown panel, as shown and described.

DESCRIPTION

FIG. 1 is a front perspective view of the crown panel showing my design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front perspective view of a cap incorporating my design.

The broken lines in FIG. 8 are for the purpose of illustrating the environment in which the design is associated and form no part of the claimed design.

1 Claim, 8 Drawing Sheets(56)
